STEAM GENERATOR

Arthur E. Raynor, Rockville Centre, N. Y., assignor to The Babcock & Wilcox Company, Rockleigh, N. J., a corporation of New Jersey

Application January 4, 1946, Serial No. 638,941

5 Claims. (Cl. 122—240)

1

This invention relates to steam or vapor generators of the type in which substantially all of the steam is generated in furnace wall tubes.

An object of the invention is the economical and efficient generation of steam throughout a wide range of boiler load requirements.

Further, an object of the invention is to provide a high capacity steam generating installation characterized by low first cost and low space requirements by reason of the utilization of highly effective heat absorbing surfaces and the arrangement of heat absorbing surfaces so as to minimize the amount of thermal insulation required.

The invention will be described with reference to the accompanying drawings showing a preferred embodiment of the invention, and other objects of the invention will appear as the description proceeds.

In the drawings:

Fig. 1 is a vertical section on the line 1—1 of Fig. 2 through the steam generator, indicating the construction of the furnace and the relation of the convection section thereto;

Fig. 2 is a vertical section on the line 2—2 of Fig. 1 through the multiple furnaces of the installation, showing the division wall between the furnaces;

Fig. 3 is a plan section on the line 3—3 of Fig. 1, showing the hopper bottoms of the furnaces and arrangement of the groups of tubes in the furnace division wall;

Fig. 4 is a partial plan showing the arrangement of the top water wall headers with reference to the furnace sections and the steam and water drum;

Fig. 5 is a detail view showing the construction of a furnace division wall, on an enlarged scale;

Fig. 6 is a partial elevation of the upper part of the furnace division wall taken as indicated by line 6—6 of Fig. 5 and the associated arrows;

Fig. 7 is a fragmentary horizontal section of a part of the furnace division wall taken as indicated by the line 7—7 and associated arrows in Fig. 6;

Fig. 8 is a fragmentary elevation taken as indicated by the arrows at 8—8 in Fig. 5. This view shows the manner in which the tubes of one group of division wall tubes are secured together;

Fig. 9 is a partial horizontal section on the section line 9—9 of Fig. 8; and

Fig. 10 is a partial section of the hopper bottom tubes taken on the line 10—10 of Fig. 5.

The divided furnace construction indicated in Fig. 2 of the drawings contributes to the generation of a maximum amount of steam within given space requirements by providing steam generating wall tubes subject to heat absorption from the separate combustion chambers, 10 and 12 on opposite sides thereof.

2

Fig. 2 illustrates sets of pulverized fuel burners 14—17 arranged at the top of the combustion chambers 10—12 and firing downwardly thereto. When these burners are in operation, furnace gases flow through the combustion chambers to the gas inlet 20 of the convection section 22. In this section, gases first pass over the spaced tubes of the superheater 24 and then over the tubes of the economizer 26 to a flue 28. Beyond the 10 economizer, the gases pass over the circulators leading from the furnace wall tubes to the steam and water drum 30.

The walls of the combustion chambers 10 and 12 are formed by upright steam generating tubes 15 connected into boiler circulation, and the tubes of the furnace division wall are likewise connected into the boiler circulation by reason of the connection of their inlet ends to the lower headers 32 and 34 which are, in turn, connected to the 20 water space of the drum 30 by the downcomers 36 and 38 and the downcomer connections 40. At their upper ends the wall tubes are connected to the drum 30 through a plurality of separate relatively small diameter headers 42, 43, 44, and 45, and their associated circulators. The headers 42 and 44 extend entirely across the top of the division wall and each has only a fraction (about 25%) of the total number of division wall tubes connected thereto (tubes nearest the observer in Fig. 2) while the headers 43 and 45 extend only half-way across the width of the division wall. Each of these headers has about one-half of the remainder of the division wall tubes secured thereto. The header 42 is L-shaped, and has an 30 outlet leg 46 extending at a right angle to the front-to-rear main part of the header, and disposed in substantial parallelism to the drum 30. The circulators such as 48 directly connect the outlet leg 46 to the drum 30. The companion header 44 is similar to the header 42 except that its right-angled outlet leg extends in a direction opposite to the outlet leg 46. It is similarly 35 directly connected to the steam and water drum 30. The short header 45, disposed directly below 40 header 44 has an outlet leg 51 extending at right angles thereto and in substantial parallelism to the drum 30, similar circulators 54—56 connecting the outlet leg 51 to the drum 30.

The other short header 43 is similar to the 50 header 45, with its outlet leg disposed directly below the outlet leg 46 of header 42.

The tubes of the furnace division wall are in single row wall alignment near the top of the furnace as indicated in Figs. 2, 5, and 7, and 55 they are held in such alignment by the arrangement of short sections of rods or bars 70—75, shown in Figs. 6 and 7. In this construction the rod section 73 is welded to the tube 80 and the rods 72 and 74 are welded to the opposite 60 sides of the next tube 82. Rod section 75 is

welded to tube 84. This arrangement is continued across the face of the division wall.

At a position in front and also well above the convection section gas inlet 20, the furnace division wall tubes are divided into groups with the tubes of a group, such as the tubes 90-97 (Figs. 8 and 9), rigidly secured together by the welding of interposed rod or bar sections 110-116 to each of two adjoining tubes. Adjoining groups of tubes are bent oppositely as indicated in Figs. 2, 3, and 5, so that they extend oppositely into adjacent furnaces or combustion chambers. One group, for instance, will assume the position of the tube section 99 (Fig. 5) and the adjoining group will assume the position indicated by tube section 130.

The lower parts of the groups of tubes have relatively short, bent, or truss sections, as indicated at 132 and 134 in Fig. 5. These sections converge downwardly into single row alignment at the position indicated at 136. At this position, the tubes of adjacent groups are rigidly secured together, as by welding. Above the short truss sections 132 and 134, longer truss sections 130 and 98 extend to the upper part of the division wall where the adjoining groups of tubes converge into single row alignment. Through the use of opposite composite groups of tube sections displaced from the vertical axial plane of the wall, a truss-like effect is attained which provides a relatively stiff and stable perforated partition wall adapted to variable pressure and temperature conditions of the multiple chambers furnace arrangement.

By reason of the securement of a plurality of tubes in groups as above described, and by reason of the opposite bending of the groups, long A-shaped openings are provided between the combustion chambers 10 and 12, in order that pressure conditions may be equalized and, in order that there may be no damage by a pressure puff in one combustion chamber, or by other unusual combustion conditions. Also, the division wall is rigidified by the truss construction so that the vibration due to operating conditions is minimized. Furthermore, the securement of the adjacent division wall tubes into groups decreases the number of horizontally extending crotches apt to promote the accumulation of ash or slag and other residue products of combustion, and provides relatively wide inclined surfaces over which such solids may readily slide into the hoppers at the bottoms of the furnaces.

Below the truss constructions of the furnace division wall and below the position 136 of single row tube alignment, alternate division wall tubes are bent toward the header 34 and the intervening tubes are bent toward the header 32. The former are welded to hopper tube sections 140 of greater diameter and the latter are similarly welded to a larger diameter hopper tube sections 142. The junctions of these larger diameter hopper tube sections with the upper division wall tubes are indicated at 144 and 146. Because of the wider spacing of the hopper tube sections 140 and 142, there are welded thereto flat studs as indicated at 150-159 in Fig. 10.

Near the upper ends of the hopper tube sections 140 and 142 these sections are tied together by tension members such as 160 and intermediate the lengths of the hopper tube wall sections the hopper tubes are supported at positions 162 and 164 by structural members 165-170 which are preferably supported by the furnace walls extending at right angles to the division

wall, so that all of the walls, including the sloping section of the hoppers will move together with changes of temperature.

Fig. 3, taken on the section line 3-3 of Fig. 1, shows the arrangement of the groups of division wall tubes, the oppositely bent groups, or truss sections being indicated at 180-189. At the right of the group 180 three tubes, above the hoppers, are bent into a single row alignment transversely of the general direction of the division wall as indicated at 196 and at the opposite side of the division wall three tubes 198-200 are similarly bent. This arrangement leaves free communication spaces at the ends of the division wall, establishing additional intercommunication between the combustion chambers 10 and 12 above the furnace hoppers.

The furnace front wall 210 (Fig. 1) is defined by steam generating tubes 212 extending upwardly from the lower header 214 which is in communication with the water space of the drum 30 through downcomers such as 36 and 38, and other downcomer connections. From the top header 216 the furnace roof tubes such as 218 extend through the upper part of the convection gas pass to the drum 30.

From the rear furnace wall header 220, directly connected to the downcomers 222, steam generating tubes 224 extend vertically along the lower rear wall section 226, and thence along the inclined wall 228 at the lower part of the convection section. These tubes then extend in a plurality of rows and in staggered relation in a screen formation across the upward flow of gases into the convection gas pass, forming the screen 230. Beyond the screen the tubes are disposed in single row alignment, forming the wall 232 separating the furnaces and the convection gas pass. At the top of this wall the steam generating tubes have bent circulator sections such as 234 and 235 extending across the gas flow at the top of the convection section, to the drum 30.

The furnace side walls 240 and 242 (Fig. 2) are likewise defined by upright steam generating tubes. These tubes, indicated at 244 and 246, extend upwardly from lower headers 248 and 250 which are supplied with water through the downcomer connections 252 and 254. They first extend along the inclined hopper walls 256 and 258, and then vertically to the top of the furnaces. They are there connected to headers, there being two headers for each of the walls 240 and 242. For the wall 240 the two top headers are indicated at 260 and 262. The upper header 260 has about one-half of the wall tubes connected thereto, these being the tubes over the front half of the wall 240. This header extends throughout the full width of the wall and has a right angled leg extending in substantial parallelism to the steam and water drum. This rear leg is directly above the rear leg 262' of the lower header 262, and it is directly connected to the drum 30 by the horizontal circulators 264. The header 260 is L-shaped, and it is similar to the header 280 (for the wall 242) which appears in Fig. 4. In the lower half of this figure, the lower headers are shown in full lines, and in the upper half the top headers are shown in full lines. The lower header 262 has rear and side wall legs 262' and 262'' with the side wall leg extending across one-half of the width of the wall 240 and having the remainder of the tubes of that wall directly connected thereto. The rear leg 262' is directly connected to the steam and water drum 30 by horizontal circulators such as 266.

The headers 260 and 262, and through them the wall 240, are suspended from the steelwork 268 by hangers 270, so that the entire wall is free to expand downwardly.

The opposite side wall 242 has its tubes similarly connected to the long header 280 and a shorter header directly underneath, with the rear legs of these headers similarly disposed in parallelism to the drum 30 and connected thereto by the horizontal circulators such as 272 and 274.

Preferably, the above described furnace wall tubes are, for the most part, arranged in contact, as indicated in Fig. 3, but at the side walls of the convection section the tubes 300 and 302 are spaced apart. Similarly, the downcomer tubes 36 and 38, along the rear wall of the convection section are spaced apart, with the spaces between the tubes 38 closed by blocks 304 of thermal insulation. The outer downcomer tubes 36 are enclosed by thermal insulation 306 in the space between the blocks 304 and the outer wall 308.

What is claimed is:

1. In a vapor generator, a furnace; a division wall separating the furnace into two furnace sections; a convection section including spaced fluid heating tubes disposed across a gas pass, said gas pass being so related to the division wall that the latter extends from a position closely adjacent an intermediate portion of the inlet of the gas pass to a position remote therefrom, the furnace sections being disposed in parallel flow arrangement relative to the inlet of the gas pass, the division wall being formed by upright vapor generating tubes with pairs of adjoining tubes having angularly related truss parts extending into opposite furnace sections from the median plane of the division wall to form A-shaped gas communication openings between the sections, metallic means mechanically connecting the truss forming tubes above and below said openings to form wall rigidifying trusses; other upright vapor generating tubes defining the remaining furnace walls; and means connecting said tubes into a fluid circulation system.

2. In a vapor generator, a furnace, a division wall separating the furnace into two furnace sections; a convection section including spaced fluid heating tubes disposed across a gas pass, said gas pass being so related to the division wall that the latter extends from a position closely adjacent an intermediate portion of the inlet of the gas pass to a position remote therefrom, the furnace sections being disposed in parallel flow arrangement relative to the inlet of the gas pass, the division wall being formed by groups of adjoining upright vapor generating tubes with pairs of adjoining groups having angularly related truss parts extending into opposite furnace sections from the median plane of the division wall to form A-shaped gas communication openings between the sections, metallic means mechanically connecting adjoining groups of tubes above and below said openings to form wall rigidifying trusses; other upright vapor generating tubes defining the remaining furnace walls; and means connecting said tubes into a fluid circulation system, the tubes of each group being mechanically tied together to provide co-acting truss components of increased strength.

3. In a vapor generator, a convection section including spaced fluid heating tubes disposed across a gas pass, a plurality of furnaces the

gases from which enter said gas pass, upright vapor generating tube defining the walls of the furnaces, some of said wall tubes defining a division wall common to the furnaces and arranged transversely of the inlet of said gas pass and extending from a position closely adjacent an intermediate portion of said inlet to a position remote therefrom, adjacent division wall tubes having oppositely bent portions with their lower and shorter parts extending into opposite furnaces and their upper and longer parts extending gradually back to divisional wall alignment at the upper part of the wall, means tying said adjoining division wall tubes together below said bent portions, and means connecting said wall tubes into a fluid circulation system.

4. In a vapor generator, a convection section including spaced fluid heating tubes disposed across a gas pass, a plurality of furnaces the gases from which enter said gas pass, said furnaces being arranged in parallel as to gas travel to said convection section, upright vapor generating tubes defining the walls of the furnaces, some of said wall tubes defining a division wall common to the furnaces and arranged transversely of the inlet of said gas pass and extending from a position closely adjacent an intermediate portion of said inlet to a position remote therefrom, adjacent division wall tubes having oppositely bent portions with their lower and shorter parts extending into opposite furnaces and their upper and longer parts extending gradually back to divisional wall alignment at the upper part of the wall, means tying said adjoining division wall tubes together below said bent portions, and means connecting said wall tubes into a fluid circulation system.

5. In a vapor generator, a convection section including spaced fluid heating tubes disposed across a gas pass, a plurality of furnaces the gases from which enter said gas pass, said furnaces being arranged in parallel as to gas travel to said convection section, upright vapor generating tube defining the walls of the furnaces, some of said wall tubes defining a division wall common to the furnaces and arranged transversely of the inlet of said gas pass and extending from a position closely adjacent an intermediate portion of said inlet to a position remote therefrom, adjacent groups of division wall tubes having oppositely bent portions with their lower and shorter parts extending into opposite furnaces and their upper and longer parts extending gradually back to divisional wall alignment at the upper part of the wall, means tying said adjoining groups of division wall tubes together below said bent portions, and means tying together the similarly bent tubes of each group, and means connecting said wall tubes into a fluid circulation system.
